UNITED STATES PATENT OFFICE.

EDWARD B. MALLORY, OF TENAFLY, NEW JERSEY, ASSIGNOR TO WESTINGHOUSE ELECTRIC & MANUFACTURING COMPANY, A CORPORATION OF PENNSYLVANIA.

DESIGN FOR AN ESCUTCHEON PLATE.

Application filed March 23, 1926. Serial No. 17,033. Term of patent 3½ years.

To all whom it may concern:

Be it known that I, EDWARD B. MALLORY, a citizen of the United States, residing in Tenafly, in the county of Bergen and the State of New Jersey, have invented a certain new, original, and ornamental Design for Escutcheon Plates, of which the following is a specification, reference being had to the accompanying drawing, forming a part hereof.

Fig. 1 is a front elevation of my new de-

sign for an escutcheon plate, and Fig. 2 is a cross-sectional view taken along a line corresponding to the line II--II of Fig. 1.

I claim:

The ornamental design for an escutcheon plate as shown.

In testimony whereof, I have hereunto subscribed my name this 25th day of Feby., 1926.

EDWARD B. MALLORY.
